United States Patent Office

Des. 180,342
Patented May 21, 1957

180,342

HANDBAG

Lorena Pat Reed, New York, N. Y.

Application August 20, 1956, Serial No. 42,659

Term of patent 7 years

(Cl. D87—3)

Fig. 1 is a front perspective view of a handbag embodying my new design;

Fig. 2 is a rear elevational view thereof, and

Fig. 3 is an end elevational view thereof.

I claim:

The ornamental design for a handbag, as shown.
